APPARATUS FOR DRYING FABRICS

George B. Long, Dayton, Ohio, assignor to General Motors Corporation, Dayton, Ohio, a corporation of Delaware

Application January 12, 1952, Serial No. 266,157

5 Claims. (Cl. 34—75)

1

This invention relates to domestic appliances and particularly to apparatuses for drying damp fabrics such as clothes and other articles.

An object of my invention is to provide an improved clothes drying apparatus.

Another object of my invention is to provide a novel arrangement within a clothes dryer cabinet for condensing moisture out of and removing lint from heated moist air leaving damp fabrics being dried therein.

A further object of my invention is to flow heated moist air leaving damp fabrics in a substantially closed clothes dryer cabinet through a layer or film of liquid to cool and condense moisture out of the heated air and to recirculate the cooled drying air over the damp fabrics without flowing drying air into the room in which the cabinet is located.

A still further object of my invention is to provide in a clothes dryer cabinet a body of liquid and means for elevating some of the liquid above the body thereof and to spread the elevated liquid out into a sheet or film through which heated moist air leaving damp fabrics flows, to cool the liquid from the film thereof and return the cooled liquid to the body of liquid in the cabinet while at the same time collecting in the cabinet water condensed out of the heated moist air.

In carrying out the preceding object, it is a further and more specific object of my invention to direct the liquid from the film thereof through a heat exchanger and to cool the liquid passing therethrough by circulating air exteriorly of the dryer cabinet over the heat exchanger.

Further objects and advantages of the present invention will be apparent from the following description, reference being had to the accompanying drawings, wherein a preferred form of the present invention is clearly shown.

In the drawing:

Fig. 1 is a vertical sectional view of a clothes dryer cabinet having my invention embodied therein; and

Fig. 2 is a sectional view taken on the line 2—2 of Fig. 1.

Referring to the drawing for illustrating my invention, I have shown in Fig. 1 thereof a clothes dryer cabinet including a base wall 11, a top sheet metal wall 12, side walls 14, rear wall 16 and a front wall 17 (see Fig. 2). The front wall of the cabinet has an opening therein, normally closed by a door, affording access to a clothes dryer container or drum within the cabinet as is conventional in the art. These walls 11, 12, 14, 16 and 17 are constructed and

arranged to provide a substantially closed cabinet which excludes air from the room in which the cabinet is located. A damp fabric or clothes receiving container or drum comprising a cylindrical sheet metal wall 18 having a plurality of perforations 19 therein and a front and back wall is rotatably mounted within a stationary casing 21 located within the walls of the cabinet. The cylindrical wall 18 of the container or drum is provided with integrally formed and inwardly directed vanes 22 which serve to tumble or agitate damp fabrics when the drum is rotated. Casing 21 is provided with an air inlet opening 23 and an air outlet opening 24. Electric heaters 27 are mounted on arcuate-shaped, in cross section, reflectors or the like 28 which may be carried on a plate removably attached to casing 21 adjacent the air inlet opening 23 thereof. These heaters 27 extend inwardly of a wall of casing 21 over a substantial portion of the rotatable clothes drum and are connected to a source of electric supply through any suitable or well-known manually set timer or chronometric switch means which also controls operation of a motor to be presently described. The casing 21 may be surrounded with suitable insulating material so as to confine heat generated in the dryer cabinet to the space within this casing as is conventional in the art.

A substantially cylindrical shaped sheet metal element 31 is preferably insulated from casing 21 and is suitably attached to its lower part to form a downwardly directed continuation thereof. The bottom of element 31 is bent inwardly as at 32 and upwardly as at 33 to provide a circular trough about the lower portion thereof. A spider or web-like bracket 36 is disposed within the sheet metal element 31 and is welded or otherwise suitably secured to its wall. Bracket 36 forms a bearing for supporting a vertical shaft 37 centrally of element 31. A fan or blower 38 is mounted on the enlarged portion of shaft 37, above bracket 36, and a bevel gear 39 is secured to the upper end of shaft 37. Another bevel gear 41 is mounted on the end of a shaft 42 of an electric motor 43. Motor 43 is preferably located outside casing 21 and its shaft 42 projects thereinto for permitting gear 41 to register or mesh with the gear 39 for rotating shaft 37. Motor 43 has mounted on the other end of its shaft 42 a double pulley 46. One portion of the double pulley 46 carries a belt 47 which rides over a pulley 48 mounted on a horizontal drive shaft of container or drum 18 for rotating the same. The other portion of double pulley 46 carries a

belt 49 which rides over a pulley 51 mounted upon a shaft 52 (see Fig. 2) rotatably supported in a bearing provided on a webbed or spider-like plate 53. Plate 53 is secured to the rear wall 16 of the dryer cabinet in any suitable or conventional manner. A sleeve 56 extends between the rear and front walls 16 and 17, respectively, of the dryer cabinet and provides an air passage or tunnel 57 through the cabinet which communicates with the air in the room in which the cabinet is located. A grill of screen 58 may be disposed over the front end of passage or tunnel 57. A fan or blower 59 is mounted on shaft 52 for circulating air through the passage or tunnel 57.

The reduced portion 61 of vertical fan shaft 31 depends from the supporting spider 36 and has a truncated cone-shaped combined pump and flinger member 62 mounted thereon in any suitable or well-known manner. This combined pump and flinger member 62 may be constructed of any suitable or desirable material so that when the same is rotated it will elevate a liquid, such as water, into which its lower end depends and will fling the elevated water laterally from its upper end in the form of a horizontal sheet, layer or film of liquid extending from the truncated member 62 to the inner wall surface of casing extension element 31. Walls of a receptacle 66 form a large pocket 67 therein and integral walls 68 and 69 thereof form a smaller and shallow pocket 71 therein. Receptacle 66 is slidably and removably supported upon an open ended tray-like element 73 having four legs 74 pivotally attached thereto. The lower ends of legs 74 are pivotally mounted to lugs 75 welded or otherwise suitably secured to the metal base 11 of the dryer cabinet. A bracket 76, also welded or otherwise suitably secured to the metal base 11, forms a stop for the receptacle 66 as will be presently described. An opening formed in the one side wall 14 of the dryer cabinet provides access to the receptacle 66 and this opening is normally closed by a hinged door 78. The tray-like element 73 is swung, by virtue of the pivoted leg arrangement disclosed, from its elevated position shown in full lines in the drawing into a lower position, shown in dot-dash lines in the drawing, whereupon the receptacle 66 may be slid off element 73 and removed from the dryer cabinet. The pivotal movement of element 73 and consequently receptacle 66 permits the top edge of wall portions of the receptacle and top edge of upright wall 68 of pocket 71 to free the lower end of truncated cone member 62 for a purpose to be hereinafter described. It is to be understood that when element 73 and receptacle 66 are in the elevated position, illustrated in the drawing, both have been moved to a position beyond the vertical alignment of the upper and lower pivot points of the ends of legs 74 and thereby rest against the stop bracket 76.

A pipe 81 is secured to the lower portion of casing extension 31 and communicates with the trough formed in the bottom thereof. This pipe 81 extends through a wall of sleeve 56 and is connected to a header portion 82 of a heat exchanger 83 (see Fig. 2) located in the passage or tunnel 57. The lower part of heat exchanger 83 has a header portion 84 provided with an outlet pipe 86 which also extends through a wall of sleeve 56 and has its end 87 terminating above the shallow pocket 71 in receptacle 66. Heat exchanger 83 may be of any suitable or conventional construction and preferably comprises a plurality of finned conduit loops communicating at their

upper ends with header 82 and communicating at their lower ends with header 84 to provide a closed path of flow for liquid therethrough.

Prior to operating the present appliance small pocket 71, which may hold approximately a gallon of water, is filled with water and the receptacle 66 is then elevated to the position shown in full lines in the drawing, whereby the lower end of member 62 is submerged in the water contained in pocket 71. Damp fabrics are placed in the container or drum 18 and thereafter the timer switch of the appliance is manually set for a predetermined timed clothes drying cycle of operation. The switch simultaneously energizes electric heaters 27 and motor 43 to impart heat to the fabrics, to rotate container or drum 18, to drive the fans or blowers 28 and 59 and to also rotate member 62. While the damp fabrics in the rotating drum 18 are being heated, air within the dryer cabinet is circulated by fan 38 into casing 21 by way of the air inlet opening 23 in the upper portion thereof. This air flows into drum 18 through the perforations 19 therein and over or across damp fabrics contained in the drum. The air in passing over the heated damp fabrics absorbs moisture released therefrom and the heated moist air is circulated downwardly in casing 21 through the spider-like bracket 36. Simultaneously therewith member 62 is elevating water from the body thereof contained in pocket 71 of receptacle 66 and is discharging the water at its upper end in the form of a sheet, layer or film in the path of flow of the heated moist air. Fan 38 thus blows the heated moist air leaving the damp fabrics through this sheet or film of liquid which liquid cools and condenses moisture out of the heated air, and effectively removes lint from the heated moist air which lint is eventually collected in the receptacle 66. Water condensed out of the heated moist air, by its flow through the film of liquid, may fall directly into the receptacle 66 or it may follow the film of liquid into the trough in the lower end of casing 21. Water from the trough is directed, by pipe 81, into the heat exchanger 83 and is cooled by room air circulating over the heat exchanger by operation of fan 59 simultaneous with operation of fan 38. The cooled water leaves the exchanger 83 by way of pipe 86 and its end 87 discharges the water into the small shallow water pocket 71 of receptacle 66. Wall 68 of pocket 71 maintains a suitable body of water at a predetermined level in pocket 71 to insure immersion therein of the lower end of member 62. Excess water entering the pocket 71 overflows its wall 68 and falls into the larger water collecting pocket 67 of receptacle 66. The pocket 67 is preferably of a size to have a capacity for water accumulation sufficient to permit several clothes drying operations of the apparatus without too frequently emptying water therefrom. At the end of a complete clothes drying operation, door 78 is opened and receptacle 66 is pulled toward the opening, normally closed by door 78, whereupon the receptacle 66 may be slid off its support 73 and removed from the cabinet to empty water and lint therefrom. To facilitate the act of lifting and emptying receptacle 66 I may provide the same with a bail handle or the like.

It should, from the foregoing, be apparent that I have provided an improved method of, and apparatus for, condensing moisture out of air employed for circulation over damp fabrics being dried in a clothes dryer cabinet. By flowing heated moist air leaving damp fabrics through a

substantially sheet-like layer or film of water, a more effective contact of the air with the water is obtained to provide efficient cooling of the air. Also by confining the circulation of drying air to within the dryer cabinet, no moist air is discharged into the room in which the cabinet is located and consequently the humidity in the room is not increased. Cooling of the liquid employed to condense water out of heated moist air by air from the room in which the dryer cabinet is located and circulating the cooled liquid for use again eliminates the necessity of extending a water supply pipe line to the cabinet. Also by providing a removable water collecting receptacle in the dryer cabinet the cabinet may be installed in basements or utility rooms which are devoid of floor drains.

While the form of embodiment of the invention as herein disclosed constitutes a preferred form, it is to be understood that other forms might be adopted, as may come within the scope of the claims which follow.

What is claimed is as follows:

1. An apparatus for drying damp fabrics comprising in combination, a substantially closed cabinet, a container within the said cabinet for receiving fabrics to be dried, means for agitating the fabrics in said container, means for imparting heat to the fabrics, a casing within said cabinet about said container and provided with an air inlet opening and an air outlet opening, means for circulating air within said cabinet into said casing through said inlet opening over fabrics in said container and out of said casing through said outlet opening whereby the air in passing over the heated damp fabrics absorbs moisture released therefrom, a removable receptacle disposed in said cabinet, said receptacle containing a body of liquid, a rotatable truncated cone-shaped member having its lower end immersed in said body of liquid, said member being adapted upon rotation thereof to elevate liquid from said body thereof in said receptacle and to discharge the elevated liquid in a film in the path of flow of heated moist air leaving the fabrics to cool and condense moisture out of the heated air, a trough for receiving liquid from said film thereof, means for directing liquid from said trough into a heat exchanger, means for circulating air from exteriorly of said cabinet over said heat exchanger to cool the liquid therein, and means for returning liquid cooled in said heat exchanger to said body thereof in said receptacle.

2. An apparatus for drying damp fabrics comprising in combination, a substantially closed cabinet, a container with the said cabinet for receiving fabrics to be dried, means for agitating the fabrics in said container, means for imparting heat to the fabrics, a casing within said cabinet about said container and provided with an air inlet opening and an air outlet opening, means for circulating air within said cabinet into said casing through said inlet opening over fabrics in said container and out of said casing through said outlet opening whereby the air in passing over the heated damp fabrics absorbs moisture released therefrom, a removable receptacle within said cabinet, said receptacle being partitioned into a shallow pocket and a relatively deep pocket, said shallow pocket containing a body of liquid, a rotatable truncated cone-shaped member having its small end immersed in said body of liquid, said member being adapted upon rotation thereof to lift liquid upwardly from said body thereof in said shallow receptacle pocket and to fling the

5 elevated liquid from its larger ends in the form of a film in the path of flow of heated moist air leaving the fabrics to cool and condense moisture out of the heated air, means for cooling liquid flowing from said film thereof with air exteriorly of said cabinet, means for directing the cooled liquid back into said receptacle shallow pocket, and a wall portion of said shallow pocket terminating below the top of walls of said receptacle to permit liquid to overflow the shallow pocket and fall into said receptacle deep pocket.

10 3. An apparatus for drying damp fabrics comprising in combination, a substantially closed cabinet, a container within the said cabinet for receiving fabrics to be dried, means for agitating the fabrics in said container, means for imparting heat to the fabrics, a casing within said cabinet about said container and provided with an air inlet opening and an air outlet opening, means for circulating air within said cabinet into said casing through said inlet opening over fabrics in said container and out of said casing through said outlet opening whereby the air in passing over the heated damp fabrics absorbs moisture released therefrom, a receptacle in said cabinet adapted to contain a body of liquid, means for elevating liquid from the body thereof in said receptacle and for generating a film of liquid across the path of flow of heated moist air leaving the fabrics to cool and condense moisture out of the heated air, means forming a passage extending continuously through said cabinet and communicating with air exteriorly thereof, a heat exchanger disposed in said passage, means for directing liquid from said film into said heat exchanger, means for directing liquid from said heat exchanger back to the body of liquid in said receptacle, and means for circulating air through said passage over said heat exchanger to cool the liquid therein prior to its flow into said receptacle.

15 4. An apparatus for drying damp fabrics comprising in combination, a substantially closed cabinet, a container within the said cabinet for receiving fabrics to be dried, means for agitating the fabrics in said container, means for imparting heat to the fabrics, a casing within said cabinet about said container and provided with an air inlet opening and an air outlet opening, means for circulating air within said cabinet into said casing through said inlet opening over fabrics in said container and out of said casing through said outlet opening whereby the air in passing over the heated damp fabrics absorbs moisture released therefrom, a removable receptacle within said cabinet, said receptacle being partitioned into a shallow pocket and a relatively deep pocket, said shallow pocket containing a body of liquid, means for elevating liquid from said body thereof and for generating a film of liquid across the path of flow of heated moist air leaving the fabrics to cool and condense moisture out of the heated air, means for cooling liquid flowing from said film with air exteriorly of said cabinet, means for directing the cooled liquid back into said receptacle shallow pocket, and a wall portion of said shallow pocket terminating below the top of walls of said receptacle to permit liquid to overflow the shallow pocket and fall into said receptacle deep pocket.

20 5. An apparatus for drying damp fabrics comprising in combination, a substantially closed cabinet, a container within the said cabinet for receiving fabrics to be dried, means for agitating the fabrics in said container means for imparting

heat to the fabrics, a casing within said cabinet about said container and provided with an air inlet opening and an air outlet opening, means for circulating air within said cabinet into said casing through said inlet opening over fabrics in said container and out of said casing through said outlet opening whereby the air in passing over the heated damp fabrics absorbs moisture released therefrom, a receptacle in said cabinet adapted to contain a body of liquid, means for elevating liquid from the body thereof in said receptacle and for generating a film of liquid across the path of flow of heated moist air leaving the fabrics to cool and condense moisture out of the heated air, means within said cabinet forming a passage sealed from air circulated in the closed cabinet, a heat exchanger disposed in said passage, means for directing liquid from said film into said heat exchanger, said passage having an inlet and an

outlet communicating with air exteriorly of said cabinet for the flow thereof through said passage and over said heat exchanger to cool the liquid therein, and means for directing liquid cooled in said heat exchanger back to the body of liquid in said receptacle.
